US00D910659S

(12) **United States Design Patent** (10) Patent No.: **US D910,659 S**
 Varghese et al. (45) Date of Patent: **** Feb. 16, 2021**

(54) **DISPLAY SCREEN WITH ANIMATED GRAPHICAL USER INTERFACE**(71) Applicant: **Google LLC**, Mountain View, CA (US)(72) Inventors: **Sujit Varghese**, New York, NY (US); **Barine Tee**, East Stroudsburg, PA (US); **Jonathan Yu**, Surry Hills (AU); **Harold H. W. Kim**, Montville, NJ (US); **Jonathan Jarvis**, New York, NY (US); **Daniel Young**, Santa Clara, CA (US); **Karl Channell**, San Francisco, CA (US)(73) Assignee: **GOOGLE LLC**, Mountain View, CA (US)(***) Term: **15 Years**(21) Appl. No.: **29/696,603**(22) Filed: **Jun. 28, 2019**

CLAIM

The ornamental design for a display screen with animated graphical user interface, as shown and described.

DESCRIPTION

FIG. 1 is the first image in the sequence of the display screen with animated graphical user interface;

FIG. 2 is the second image in the sequence;

FIG. 3 is the third image in the sequence;

FIG. 4 is the fourth image in the sequence;

FIG. 5 is the fifth image in the sequence;

FIG. 6 is the sixth image in the sequence;

FIG. 7 is the seventh image in the sequence; and,

FIG. 8 is the eight image in the sequence.

The appearance of the animated user interface sequentially transitions between the images shown within FIGS. 1-8. The process or period in which an image sequence transitions from one image to another image forms no part of the claimed design.

The broken line showing of the user and the display screen in all views is lines showing a finger, a display screen, and portions of the graphical user interface are for environmental purposes only and forms no part of the claimed design.
